UNITED STATES PATENT OFFICE.

ARTHUR W. BROWNE, OF PRINCE BAY, NEW YORK, ASSIGNOR TO THE S. S. WHITE DENTAL MANUFACTURING COMPANY, A CORPORATION OF PENNSYLVANIA.

DENTAL CHAIR.

1,236,401.

Specification of Letters Patent. Patented Aug. 14, 1917.

Application filed August 14, 1915. Serial No. 45,538.

To all whom it may concern:

Be it known that I, ARTHUR W. BROWNE, a citizen of the United States, and a resident of Prince Bay, in the county of Richmond, State of New York, have invented certain new and useful Improvements in Dental Chairs, of which the following is a specification, reference being had to the accompanying drawings.

10 My invention relates particularly to foot-
rests for dental chairs, and is especially di-
rected to that class of foot-rests which in-
clude means to vary their relation to the
chair seat to accommodate the varying leg
15 measurement of different patients.

The principal object of my invention is to
provide a foot-rest with such a wide range
of movement that it will afford ample sup-
port for even the smallest patient.

20 Other objects of my invention are, to pro-
vide a foot-rest having a movable rest por-
tion adapted to be swung toward and from
the chair seat, and readily locked and re-
leased by means actuated by the foot of the
25 operator; and to provide means thereon with
which the heels of the patient may be en-
gaged to prevent the accidental displace-
ment of the patient's feet therefrom, where-
by the patient is afforded a feeling of se-
30 curity and confidence.

My invention comprehends a foot-rest so
proportioned, arranged and balanced, that
it may be adjusted, locked and released by a
comparatively light pressure and slight turn
35 of the operator's foot.

My invention also includes all of the va-
rious novel features of construction and ar-
rangement hereinafter more definitely spe-
cified.

40 In the accompanying drawings, Figure 1
is a side elevational view of a dental chair
conveniently embodying a foot-rest con-
structed in accordance with my invention;
Fig. 2 is a plan view, on a much larger scale,
45 of the foot-rest shown in Fig. 1, detached
from the chair proper; Fig. 3 is a central
vertical longitudinal sectional view of the
foot-rest and that portion of the chair
frame to which it is attached; and Fig. 4 is
50 a fragmentary sectional view of the mecha-

nism for locking the movable portion of the
foot-rest in different positions.

In said figures, the chair comprises the
frame 1, seat 2, back 3, head-rest 4 and arm-
rest 5, and has the usual depending brackets 55
6 which carry a step or platform 7.

Upon the free forward ends of the
brackets 6 the main foot-rest frame may be
detachably mounted and rigidly secured
thereto in any suitable manner. The main 60
foot-rest frame is generally rectangular in
form, and comprises the side rails 10, con-
nected by the transverse bars 11, 12, 13 and
14. The transverse bars 11 and 12, and that
portion of the side rails 10 which is included 65
therebetween are provided with an inwardly
extending flange 15, forming a recess ar-
ranged to receive the foot-board 16, which
is supported upon said flange 15. The por-
tions of the side rails 10 which are disposed 70
between the transverse bars 12 and 13 are
slightly curved downwardly and merge into
the terminal portions 17 which extend ob-
liquely upward and which are connected at
the outer ends by the transverse bar 14, car- 75
rying a rest 18 for the feet of patients hav-
ing comparatively long or maximum leg
measurement.

The main foot-rest frame is provided with
an auxiliary foot-rest frame, which is ad- 80
justably carried thereby and which is
mounted to rock upon the shafts 19 project-
ing from lugs 20 on said main foot-rest
frame. The side rails 22 of the auxiliary
foot-rest frame extend in planes laterally 85
beyond or outside the side rails 10 of the
main foot-rest frame, and have the trans-
verse bar 23 at its free end normally overly-
ing the transverse bar 13, affording a rest
for patients having shorter leg measurement 90
than would be accommodated by the trans-
verse bar 14.

The transverse bar 23 is connected by a
plurality of suitably spaced longitudinally
extended webs 24 with the transverse bar 25, 95
which, as best shown in Fig. 3, connects the
side rails 22 of the auxiliary foot-rest frame
and is disposed in oblique relation to the
plane of the webs 24 and forms with the
downwardly curved rear margin of the 100

transverse bar 23, a transversely extended pocket into which the heels of the patient may project so as to enter the open spaces 26 between the longitudinal webs 24, which, 5 as best shown in said Fig. 3, extend across the bottom of said pocket and afford a feeling of security and confidence to the patient.

The transverse bar 23 of the auxiliary foot-rest frame normally overlies the transverse bar 13 of the main foot-rest frame, and is arranged to be supported upon suitably disposed buffers 27 projecting from sockets 29 adjacent to the intersections of the side rails 10 of the main foot-rest frame and its 15 transverse bar 13.

The side rails 22 of the auxiliary foot-rest frame are curvedly extended rearwardly and downwardly, and are connected by the transverse bar 30, which affords suitable bearings 31 and bearing 32 for the rock-shaft 33 carrying the dog or pawl 34 disposed between the bearings 31, preferably in the median plane of the foot-rest frames, and being actuated by the foot treadle 35 on the 20 free end of said shaft 33, which extends laterally exterior to one of the side rails of 25 said auxiliary foot-rest frame.

The dog or pawl 34 is secured to the rock-shaft 33 and has its forward end 36 weighted 30 and forms a slide-block arranged to support the rack-bar 37, which has its forward end mounted to rock on the shaft 39 in the bearing lug 40 on the transverse bar 13 of the main foot-rest frame, and which has 35 teeth forming notches along its under surface arranged to be engaged by the dog or pawl 34.

As best shown in Fig. 3, the dog or pawl 34 is provided with a guard 41 for the rack-bar 37, which guard has its under surfaces disposed in relatively angular planes, that portion in the rear of its axial plane being substantially parallel with the rack-bar supporting plane of said slide-block, and that 45 portion forward of the axial plane diverging forwardly with respect to the supporting plane of said slide-block. Thus it will be readily seen that the structure including the dog or pawl 34 may have a rocking movement with respect to the rack-bar 37, while snugly fitting the same, whereby it will be 50 impossible for the rack-bar to be accidentally displaced from its proper coöperation with said dog or pawl 34.

The auxiliary foot-rest frame is so balanced by its rearwardly extending portion, which projects behind its axis of oscillation, that it may be readily swung upon said axis of rotation by a very slight pressure of the 60 operator's foot upon the treadle 35, and said auxiliary frame may be caused to be locked in any desired adjusted position by a simultaneous rocking movement of said treadle, effected by a slight twist of the operator's

foot, to bring the dog or pawl 34 into engagement with one of the respective teeth 42 of said rack-bar 37, and similarly, said dog or pawl 34 may be released from the teeth of said rack-bar to permit of its readjustment, so that the transverse rest bar 23 70 may be brought toward or from the seat of the chair as desired; or may be dropped to its normal position overlying the transverse bar 13 of the main foot-rest frame and supported upon the buffers 27. 75

It is to be noted that when the auxiliary foot-rest is disposed in its normal position as shown in the drawings, the combined structure coöperates to provide all that may be desired, both in appearance and efficiency, in all ordinary cases, and that it is possible with but little effort on the part of the operator to so adjust the auxiliary foot-rest frame with respect to the chair seat as to accommodate leg measurement of even the 85 smallest patient.

I do not desire to limit my invention to the precise details of construction and arrangement as herein set forth, as it is obvious that various modifications may be 90 made therein without departing from the essential features of my invention as defined by the appended claims.

Having thus described my invention, I claim: 95

1. In a dental chair, the combination with a seat frame, of a main foot-rest frame carried thereby, an auxiliary foot-rest frame hingedly connected with said main foot-rest frame and having an extension projecting 100 rearwardly from the plane of the axis of oscillation of said auxiliary foot-rest frame, a bar pivoted to said main foot-rest frame, and means on said extension arranged to be engaged with said bar in different predetermined positions, to sustain said auxiliary foot-rest frame in different positions with respect to said seat frame.

2. In a dental chair, the combination with a seat frame, of a main foot-rest frame carried thereby and having a footboard, an auxiliary foot-rest frame overlying said main foot-rest frame and hingedly connected therewith and embracing said footboard, pivoted means on the respective foot-rest frames 110 coöperatively connected to hold said auxiliary foot-rest frame in different adjusted positions with respect to said seat frame, and means actuated by the foot of the operator 115 for locking or releasing said auxiliary foot-rest frame and for swinging it into different positions.

3. In a dental chair, the combination with a seat frame, of a main foot-rest frame carried thereby, an auxiliary foot-rest frame 125 overlying and extending laterally beyond said main foot-rest frame and hingedly connected therewith, and having rearwardly

projecting arms extending beyond the hinged connection, and means carried by said arms for locking the auxiliary foot-rest frame in different adjusted positions with respect to said seat frame, and including a bar connected with said main foot-rest frame.

4. In a dental chair, the combination with a seat frame, of a main foot-rest frame carried thereby, an auxiliary foot-rest frame hingedly connected with said main foot-rest frame and having an extension projecting rearwardly of the plane of the axis of oscillation of said auxiliary foot-rest frame, a bar pivoted to said main foot-rest frame, and means on said extension embracing said bar and arranged to be engaged therewith in different predetermined positions, to sustain said auxiliary foot-rest frame in different positions with respect to said seat frame.

5. In a dental chair, the combination with a seat frame, of a main foot-rest frame carried thereby, an auxiliary foot-rest frame hingedly connected with said main foot-rest frame, a rack-bar hingedly connected to said main foot-rest frame, a pawl pivotally supported on said auxiliary foot-rest frame and having means for engaging the teeth of said rack-bar, and means carried with said pawl and rigidly connected thereto for preventing the accidental displacement of said rack-bar from said pawl.

6. In a dental chair, the combination with a seat frame, of a main foot-rest frame carried thereby, an auxiliary foot-rest frame hingedly connected with said main foot-rest frame and having a portion extending rearwardly of the plane of the axis of oscillation of said auxiliary foot-rest frame, a rack-bar pivoted to said main foot-rest frame and extending rearwardly beneath said frames, a pawl pivotally supported in said rearwardly extending portion and having a weight tending to rock it into engagement with the teeth of said rack-bar, and also having a guide provided with relatively angular surfaces alternately engaging said rack-bar in accordance with the operative or inoperative position of said pawl, and arranged to prevent the accidental displacement of said rack-bar therefrom.

7. In a structure of the class described, a main foot-rest frame, an auxiliary foot-rest frame pivoted thereto and having a portion extending rearwardly of the pivotal axis, a rack-bar pivotally connected with said main foot-rest frame, and a rocking member carried by the rearwardly extending portion arranged to engage said rack-bar to hold said auxiliary foot-rest frame in different positions, and comprising means for engaging the teeth of said rack-bar, means tending to tilt said rocking member into operative engagement with said teeth, and means for

preventing the accidental displacement of said rack-bar, and having relatively angular surfaces arranged to alternately engage said rack bar in accordance with the position of said rocking member.

8. In a device of the class described, the combination with a main foot-rest frame, of an auxiliary foot-rest frame hingedly connected therewith and having a projecting portion extending rearwardly of the plane of the axis of oscillation of said auxiliary foot-rest frame, a rack-bar pivotally connected with said main foot-rest frame and extending rearwardly beneath said frames, a pawl pivotally carried by said rearwardly projecting portion and comprising means tending to rock said pawl into engagement with the teeth of said rack-bar, and affording a sliding surface for said rack-bar when said pawl is disengaged from said teeth, and a guard arranged to limit the movement of the pawl, and to prevent the accidental displacement of said rack-bar therefrom by having relatively angular surfaces alternately engaged with said rack-bar and respectively engaged therewith when said pawl is in engagement with said teeth, and when said rack-bar is in engagement with said sliding surface.

9. In a device of the class described, the combination with a main foot-rest frame, of an auxiliary foot-rest frame hingedly connected therewith and having a projecting portion extending rearwardly of the plane of the axis of oscillation of said auxiliary foot-rest frame, a rack-bar pivotally connected with said main foot-rest frame and extending rearwardly beneath said frames, a pawl pivotally carried by said rearwardly projecting portion and comprising means tending to rock said pawl into engagement with the teeth of said rack-bar, and affording a sliding surface for said rack-bar when said pawl is disengaged from said teeth, a guard arranged to limit the movement of the pawl, and to prevent the accidental displacement of said rack-bar therefrom by having relatively angular surfaces alternately engaged with said rack-bar and respectively engaged therewith when said pawl is in engagement with said teeth, and when said rack-bar is in engagement with said sliding surface, and a foot treadle operatively connected with said pawl for actuating the same and for rocking said auxiliary frame into different adjusted positions.

10. A foot-rest having a transverse pocket provided with a plurality of spaced bars forming a grating therein.

11. A foot-rest having a transverse pocket provided with a plurality of longitudinally disposed bars connecting the walls of said pocket and forming a grating therein.

12. A foot-rest having a transverse rest

bar provided with a downwardly directed inner margin connected by a series of longitudinally disposed spaced webs with a second transverse bar extending parallel with 5 said rest-bar and disposed in angular relation to the plane of said webs.

In witness whereof, I have hereunto set

my hand this 10th day of August, A. D., 1915.

ARTHUR W. BROWNE. 10
